US00D784162S

(12) **United States Design Patent** (10) **Patent No.:** **US D784,162 S**
Villarreal et al. (45) **Date of Patent:** **** Apr. 18, 2017**

(54) **TOTTLE**

(71) Applicant: **HCT GROUP HOLDINGS LIMITED**, Central (HK)

(72) Inventors: **Armando Villarreal**, Los Angeles, CA (US); **Michelle Wong**, Alhambra, CA (US)

(73) Assignee: **HCT GROUP HOLDINGS LIMITED**, Hong Kong (HK)

(**) Term: **15 Years**

(21) Appl. No.: **29/541,807**

(22) Filed: **Oct. 8, 2015**

(51) LOC (10) Cl. **09-01**

(52) U.S. Cl.

USPC **D9/724**

(57) **CLAIM**

The ornamental design for a tottle, as shown and described.

DESCRIPTION

FIG. 1 is a perspective view of a tottle showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, shown without a cap for ease of illustration;

FIG. 9 is a front view thereof, shown without a cap for ease of illustration;

FIG. 10 is a rear view thereof, shown without a cap for ease of illustration;

FIG. 11 is a left side view thereof, shown without a cap for ease of illustration;

FIG. 12 is a right side view thereof, shown without a cap for ease of illustration;

FIG. 13 is a top plan view thereof, shown without a cap for ease of illustration and shown in an enlarged scale; and, FIG. 14 is a bottom plan view thereof, shown in an enlarged scale.

The broken line portions are included to show unclaimed subject matter only and form no part of the claimed design.

1 Claim, 12 Drawing Sheets
